JOHN J. CARROLL, OF NORFOLK, VIRGINIA, ASSIGNOR TO DIXIE JUTE BAGGING CORPORATION, OF NORFOLK, VIRGINIA, A CORPORATION OF VIRGINIA

PACKING ELEMENT

Application filed March 8, 1928. Serial No. 260,097.

My invention relates to packing elements and more particularly to an improved pipe calking packing for use by plumbers.

The usual jute packing used heretofore by plumbers has been found undesirable and wasteful due to its tensile fragility. To overcome this objection many types of larger, harder fibre which detract from the value of the packing, have been employed.

10 With these objections in mind it is the all important object of this invention to provide a relatively soft packing element having requisite tensile strength to withstand excessive pressure to which it is subjected when 15 in use.

More specifically the invention provides a longitudinal packing element formed of jute in which a relatively hard core or tightly spun center is incorporated to produce a 20 stout article.

With the preceding and other objects and advantages in mind, the invention consists in the novel combination of elements, constructions and arrangement of parts to be herein- 25 after specifically referred to, claimed and illustrated in the accompanying drawings, wherein:

Figure 1 is a side elevation of a packing element constructed in accordance with my 30 invention; and

Figure 2 is a transverse section taken on line 2—2 of Figure 1 and taken on an enlarged scale.

Referring to the invention in detail a longitudinal flexible packing element 5 composed of a plurality of spirally wound jute strands 10 is provided. In practice any desired number of strands may be employed depending upon the desired diameter of the packing.

40 To strengthen each of the strands 10 a relatively hard core strand 15 is incorporated in each of the same. Each of the core strands is a tightly spun vegetable fibre body, preferably jute, of sufficient density as to give the strands a maximum tensile strength.

In order to form each of the strands 10 a plurality of jute slivers with one of the cores 15 is spun together to twist the slivers about 50 the core. The strands 10 are then spirally

twisted together by any suitable means to produce the completed article.

In practice it has been found that the combination of jute slivers and core, in addition to producing an all vegetable fibre packing, 55 coact to give a maximum strength and durability which is necessary for calking the meeting ends of heavy pipes. Should the entire packing element 5 be too large for specific needs, any number of the strands 10 may be 60 removed for use, depending upon the size of the opening to be calked.

What is claimed is:—

As an article of manufacture, a packing 65 for pipe joints comprising a plurality of fibrous strands twisted together, each of said strands comprising a core of tightly spun vegetable slivers having a plurality of similar vegetable slivers loosely twisted therearound to form a strand of appreciable thickness, 70 said tightly spun cores serving to impart tensile strength to the packing without detracting from the compressible qualities thereof.

Signed at Norfolk, in the county of Norfolk and State of Virginia, this 27th day of February, 1928.

JOHN J. CARROLL.
